[57] **CLAIM**

The ornamental design for a locking latch assembly for luggage, as shown and described.

DESCRIPTION

FIG. 1 is a top and front perspective view of a locking latch assembly for luggage showing our new design;

FIG. 2 is a top and rear perspective view thereof;

FIG. 3 is a top plan view thereof;

FIG. 4 is a side elevational view thereof; the opposite side being a mirror image;

FIG. 5 is a rear elevational view thereof;

FIG. 6 is a front elevational view thereof;

FIG. 7 is a top and rear perspective view of a second embodiment thereof;

FIG. 8 is a top plan view of the embodiment of FIG. 7;

FIG. 9 is a side elevational view of the embodiment of

FIG. 7, the opposite side being a mirror image;

FIG. 10 is a rear elevational view of the embodiment of

FIG. 7; and

FIG. 11 is a front elevational view of the embodiment of

FIG. 7.

The broken-line showing of the combination dials in FIGS. 7 and 11 being for illustrative purposes only and forming no part of the claimed design.
